UNITED STATES PATENT OFFICE

NORMAN D. MATTISON, OF NEW YORK, N. Y.

FOOTWEAR

Application filed January 13, 1930. Serial No. 420,437.

This invention relates to shoes and other footwear, hereinafter referred to as shoes. The examination and treatment of a great number of defective feet has demonstrated that one of the most common foot defects of the more serious types consists in the tendency of the foot to roll inwardly into what is known as a "pronated" position. The present invention is especially concerned with 10 this fact, and it aims to improve shoes and more especially shoe heels and the relationship of the heel to other parts of a shoe with a view to promoting correct foot balance and restoring normal muscular action and proper 15 muscular habits.

The nature of the invention will be readily understood from the following description when read in connection with the accompanying drawings, and the novel features will be 20 particularly pointed out in the appended claims.

In the drawings,

Figure 1 is a plan view of the bottom of a shoe constructed in accordance with this invention;

Fig. 2 is a similar view showing a slightly different construction embodying the invention;

Figs. 3 and 4 are views partly in section on 30 the lines 3-3 and 4-4 of Figs. 1 and 2, respectively; and

Fig. 5 is a rear elevation of the heel portion of a shoe in an inverted position showing a further modification.

Preliminary to a detailed description of 35 the constructions shown in the drawings it may be pointed out that in the act of walking the heel of the shoe strikes the ground first, the greater part of the weight coming first on the heel of the foot and an instant later being divided between the heel and the ball of the foot as the sole of the shoe comes in contact with the ground. In a normal foot, in correct balance, the pressure on the plantar 40 surface of the forepart is much heavier at the outer or left-hand side of the longitudinal median axis of the foot, indicated by the line A-B, Fig. 1, at this particular point in the step than at the inner or right-hand side 45 of said axis. In fact, very little pressure is

exerted on the ball of the foot at the inner side of this axis when the weight first comes on the forepart of the foot, provided the muscular action and the balance are correct. As the heel lifts and the body progresses forward a shift of the weight occurs, the weight then being delivered directly and evenly to the entire ball of the foot, and the foot hinging evenly at the ankle, without inrolling.

In a pronated foot the distribution of the weight is quite different. The heel, of course, strikes the ground first, but as the weight partly shifts to the forepart or ball of the foot a much greater proportion of it is impressed upon the plantar surfaces of the ball at the inner side of the axis A-B. As the heel lifts and the body moves forward a still greater proportion of the weight comes on the plantar surfaces at the inner side of the axis A-B than is the case in a normal foot. This is the reason for the irritation, callouses and bunions frequently found on the ball surface of a pronated foot under and adjacent to the great toe joint.

There is also an important difference in the distribution of muscular action in the two feet above described. That is, in a normal foot the greater part of the muscular effort is directed along what is frequently termed "the cuboid stream" or along the outer longitudinal arch of the foot, while in the pronated foot much more of the muscular effort is exerted along the "scaphoid stream", or along the inner longitudinal arch of the foot. And this difference in the distribution of muscular action has an important effect on the strains imposed on the muscles in the ankle and leg.

The present invention proposes to utilize the inrolling tendency of a pronated foot and the consequent faulty distribution of weight to create a consciousness of improper foot balance and to produce a demand for correction.

Referring now to Figs. 1 and 3, it will be observed that the tread surface of the heel there shown is divided by the longitudinal median axis A-B of the shoe into what may be termed an outer section 2 and an inner section 3, since the former of these sections

lies at the outer side of the axis A—B while the latter lies at the inner side of said axis. The main body of the heel also is divided approximately along this axis into inner and outer sections, as is clearly shown in Fig. 3. According to this invention the inner section is made of some material which is substantially more yielding and much less firm than that of which the outer section is composed. For example, if the outer section 10 2 is made of leather, the inner section 3 may be composed of a highly resilient grade of rubber; or if the outer section 2 is made of rubber of the usual characteristics used in the manufacture of rubber heels, the inner section 15 3 should be made of a softer and substantially more yielding grade of rubber, so that in any event the section 3 will be incapable of supporting the foot with the weight of the body on it at as high an elevation as the outer section, and therefore will permit the foot to roll inwardly, if it has any material tendency to do so. So far as supporting the weight of the body is concerned, the section 3 could be omitted, but such a construction obviously would be objectionable for several reasons, particularly that of appearance. The heel provided, therefore, while preferably having approximately 20 the outline of a common heel, permits the foot to rock or roll on the axis A—B at the junction of the two sections 2 and 3 as a fulcrum into an inrolled or pronated position. The action is such, however, that the 25 walker instantly becomes conscious of the inrolling of his foot and he automatically and instinctively corrects its position by rolling it outwardly, thus bringing the weight on to the flat surface of the firm outer section 2. This shifting of the weight to the 30 outer side of the longitudinal median axis A—B is exactly what is desired to improve the distribution of the weight and promote proper muscular balance. Continued use of a shoe of this character trains the foot to correct muscular habits, directs the muscular effort along the cuboid stream in the desired 35 manner, and gradually establishes correct foot usage.

In a very large proportion of pronated feet better results are obtained by using the construction shown in Figs. 2 and 4 which is not quite so radical a departure from prior standards as that shown in Fig. 1. It will 40 be observed that the longitudinal median axis A—B of the shoe passes through the central part of the second toe, and that the heel shown in Figs. 2 and 4 instead of being divided along this axis, is divided by the axis 45 C—D which extends along the inner longitudinal arch of the foot and runs parallel to the axis A—B. The position of this axis C—D can be varied considerably, but I have obtained excellent results by so locating it 50 that it runs through the inner margin of the

ball region at the great toe joint, approximately as shown in Fig. 2. It is preferable, also, for many patients not to divide the heel at the rear rounded end thereof but to leave this area integral with the outer section 4 and to stop the inner section 5 at a point somewhat forward of the region at the curved rear end. The relative proportions of the outer and inner sections 4 and 5, respectively, as shown in Figs. 2 and 4 have proved very satisfactory. These sections may be made of the same materials, respectively, as the sections 2 and 3 in the construction previously described, and the effect in wearing the shoe is approximately the same. This arrangement, however, gives a broader area at the rear end of the heel to receive the initial impact of the foot while still providing an inadequate support for the inner margin of the heel of the foot so that the foot can readily roll into a pronated position. Such inrolling is immediately impressed upon the consciousness of the individual and he tends, largely through reflex action, to correct the position of his foot instantly.

It will be noted that in both of the constructions above described the firm sections 2 and 4 of the heel are considerably larger than their cooperating yielding sections 3 and 5, respectively. Preferably this firm section, which is designed to take the weight of the body, includes both the central and outer portions of the heel. At the same time the softer and more yielding sections of the heel are made of substantial width so that a definite inrolling of the foot is permitted along a fulcrum lying between the axis of the heel and the inner edge of the heel. This axis need not necessarily lie parallel to the axis A—B, although I prefer this arrangement. In Fig. 2 the axis of the heel is shown at a—b. A person with normal feet could wear a shoe like that shown in Figs. 2 and 4 and be entirely unconscious of anything unusual in the construction of the shoe so long as his feet remained in balance.

A shoe having a heel which operates functionally substantially like that shown in Fig. 4 is illustrated in Fig. 5, the section 4' corresponding to that shown at 4 in Figs. 2 and 4, and the cutaway portion 5' permitting the inrolling which is also permitted by the yielding section 5 of the heel shown in Figs. 2 and 4, although the construction illustrated in Fig. 5 permits a somewhat greater degree of inrolling than is obtainable in that shown in Fig. 4, and in fact a greater degree than is necessary for the purposes of this invention.

It should be observed that this invention, contrary to the usual practice, permits a relatively free inward tipping or inrolling of the foot instead of bracing the foot against such inrolling as has been the usual practice heretofore. It utilizes the tendency to inroll,

however, to create a consciousness of faulty balance and to promote a demand for and an effort toward correct balance, thus strengthening the muscles which are weak and are largely responsible for the faulty foot action, building up normal muscular action and creating or restoring the proper command of balance.

While I have herein shown and described typical embodiments of my invention, it will be understood that the invention may be embodied in other forms without departing from the spirit or scope thereof.

Having thus described my invention, what I desire to claim as new is:

1. A shoe heel formed of materials of relatively different firmness and resiliency, the weight supporting area of the heel being composed of the material of greater firmness and extending over the central and outer portions of the heel and across the curved rear end thereof, and the area to be disposed below the posterior aspect of the inner longitudinal arch of the foot being largely composed of resilient material of lesser firmness.
2. A shoe portion affording firm support under the central and outer portions of the heel of the foot and across the curved rear end of the heel, that part of the shoe portion to be disposed below the posterior aspect of the inner longitudinal arch of the foot being largely composed of resilient material of lesser firmness than the supporting portion for the heel.
3. A shoe having a heel including a tread section of relatively firm material at the outer side of the longitudinal axis extending approximately through the ball region at the great toe joint and parallel to the longitudinal median axis of the shoe, said section affording firm support under the central and outer portions and across the curved rear end of the heel of the foot, and another tread section disposed below the posterior aspect of the inner longitudinal arch of the foot, said latter section being composed largely of resilient material of lesser firmness than said first section.
4. A shoe heel divided longitudinally into inner and outer sections, the outer section extending over the central and outer portions and across the curved rear end of the heel and being made of firm material capable of supporting the weight of the body, the inner section being located for disposition below the posterior aspect of the inner longitudinal arch of the foot and being largely composed of resilient material of lesser firmness than said outer section, the junction of said sections forming a fulcrum on which the heel can tip into a pronated position, said inner section permitting such tipping movement and said fulcrum lying between the central axis of said heel and the inner edge of the heel.
